UNITED STATES PATENT OFFICE.

AUGUST EIMER AND WILHELM T. WIEGAND, OF NEW YORK, N. Y., ASSIGNEES TO
STUYVESANT GLASS COMPANY, OF NEW YORK, N. Y., A CORPORATION OF NEW
YORK.

STOPCOCK.

1,349,823.

Specification of Letters Patent. Patented Aug. 17, 1920.

Application filed September 25, 1919. Serial No. 326,304.

To all whom it may concern:

Be it known that we, AUGUST EIMER, a citizen of the United States, residing at borough of Manhattan, city, county, and 5 State of New York, and WILHELM T. WIEGAND, a citizen of Germany, resident of borough of Bronx, in the city, county, and State of New York, have invented certain new and useful Improvements in Stopcocks, 10 of which the following is a specification.

This invention relates to stop-cocks for use with apparatus such as is used for vacuum pumps and in all apparatus where it is necessary to maintain a high vacuum 15 or air tight joint, and for other purposes, and our improvements are particularly directed to means whereby a mercury seal may be applied to the joint effected by a stop-cock with its ground seat, to render 20 such joint perfectly fluid tight without detracting from the readily revoluble character of the stop-cock within its seat.

With this and other objects in view, our invention consists, primarily, in the provision of means, between the stop-cock and its seat, at opposite sides of the usual transverse or oblique passage through the stop-cock, that opens or closes communication with opposite branch pipes which extend 30 from the shell or casing, whereby an annular packing of mercury may hermetically close any lengthwise passage for air or gas that might, through some irregularity in the production of the ground surfaces by 35 which the stop-cock and its shell engage, otherwise permit the passage of air or gases past the joint.

Secondly, our invention comprehends the employment of the closure device itself as 40 the source of mercury supply with which the aforesaid inclosing seal is to be effected, whether that source be caused to flow from the interior of a hollow stop-cock radially into annular grooves provided either in the 45 stop-cock itself or in the wall of its engaging shell; or whether the shell itself has the form of a vessel to contain mercury and supply the latter to such annular grooves for joint sealing purposes.

50 Other features and advantages of our invention will hereinafter appear.

In the drawings:-

Figure 1 is a vertical sectional view of a stop-cock device wherein the mercury supply is communicated from the interior of

the closure element to external sealing grooves therein.

Fig. 2 is a transverse section, on an enlarged scale, on the line 2—2 of Fig. 1.

Fig. 3 is a vertical sectional view of a 60 stop-cock device wherein the mercury supply is communicated to the sealing grooves from an external supply.

Fig. 4 is a section on the line 4—4 of Fig. 3.

Fig. 5 is a vertical sectional view of a modified form of device wherein the shell element has the form of a vessel, with an external by-pass connecting its upper and 70 lower portions.

Fig. 6 is a similar view of a further modification, without the by-pass.

Fig. 7 is a similar view of a still further modification, wherein the by-pass is provided between the closure and shell elements. 75

Fig. 8 is a section on the line 8—8 of Fig. 5.

Fig. 9 is a section on the line 9—9 of Fig. 7, and 80

Fig. 10 shows a further modification.

The structure of Figs. 1 and 2 comprehends, in highly desirable form, both the fundamental features of our invention, viz.: the provision for sealing bands of mercury to lie, between the closure and shell elements, at both sides of the valve apertures by which communication is opened and closed through the stop-cock; and also means whereby the mercury employed as a 90 seal is compactly contained within and supplied from the interior of the closure element, without the use of external containing or by-pass means of any character.

Thus, in said Figs. 1 and 2, let 1 indicate 95 the shell element of the device, having the usual branch pipes 2, 3, extending therefrom, and let 4 indicate the closure element. As seen, the closure element 4 is in the form of a hollow vessel, whose body portion is closed 100 at its base 5, toward which said body portion tapers, while having a ground external surface, to seat closely within the ground interior surface of the shell element 1, which latter is of corresponding tapered conformation, according to usual practice in stop-cock manufacture. Also the closure element 4 has a hollow head portion 6 in communication therewith by the neck 7, the head portion serving the function of a handle by 110

which the closure element may be manipulated. The said closure element is to contain mercury, which may be introduced therein through a tubular extension 8, of the head portion 6, and a stopper 9, with an air vent 9^a, may be provided for said extension 8, to prevent spilling of the mercury contents. Instead of the stopper 9, or in addition thereto, we may provide a distensible cap, as of soft rubber, to be capable of yielding in case of expansion of the closure contents, which might force out a usual form of stopper like that indicated at 9.

The closure element 4, which is provided with a transverse tube 10, opening at opposite ends through the wall of said element—said tube 10 being here shown as inclined that it may register with branches 2, 3, arranged in different horizontal planes in their relation with the shell element 1—has its wall perforated by orifices 11, which, respectively, communicate with annular grooves or channels 12, 13, formed in the outer, ground seat of said closure element, said grooves or channels lying, respectively, above and below the tube 10. Hence, with the stop-cock elements 1 and 4 assembled, and the element 4 charged with mercury, the latter will flow through the orifices 11 and fill both of the grooves or channels 12, 13, which thus constitute mercury seals that hermetically inclose the joint or valve portion of the stop-cock, thus positively and absolutely preventing the escape of air or gases in transit through the device or while held in one branch.

In the modified form of device exhibited in Figs. 3 and 4, the shell element 14 is shown as open at both ends, and the closure element 15 as solid, with annular grooves or channels 16, 17, which respectively are charged with mercury from an external tube 18, whose opposite ends connect with orifices through the shell element 14, that register with said grooves or channels when the stop-cock elements are assembled, the supply tube 18, having a reception branch 19, which may be provided with a distensible cap 20, as and for the purposes previously recited.

The modified form of device represented in Figs. 5 and 8, differs from the foregoing in that the shell element itself here becomes the mercury container, said shell element, as 21, having the form of a vessel, with closed base 22, and an open top 23, for the admission of mercury, while, if desired, suitable covering means (not shown) may be employed for said open top. The closure element 24, is solid in this form of our invention, and has the annular grooves or channels 25, 26. There is also an expansion tube 27, that connects the base and upper portions of the shell element. In practice, the shell element is charged with mercury, and then the closure element 24, is introduced therein,

the displacement of mercury thereby in the base of the shell element causing the mercury to well up through a vertical groove 24^a, along element 24, into the groove or channel 26, and also causing mercury from the upper shell portion to flow down through a vertical groove 24^b, along element 24, into the groove or channel 25. The expansion tube 27, instead of connecting with the upper shell portion may be open to the atmosphere at its upper end, as indicated in dotted lines.

The modified form of stop-cock device of Fig. 6 shows the closure element 28, as solid except for its diagonally transverse communicating passage 29. In this example, the shell element 30, has the form of a vessel with closed base 31, to which there is applied an opening 32, provided with a distensible cap 32^a to allow for expansion.

Said shell element 30, is provided on its inner surface with the annular grooves or channels 33, 34, and mercury, with which said shell element is to be charged, will upon displacement by the entering closure element, well up between the adjacent surfaces of the closure and shell elements to fill the groove 33, the groove 34 being supplied through a vertical groove 34^a.

In the further modified form of our invention, illustrated in Figs. 7 and 8, the closure element 35, is of solid character and the shell element 36, is open ended, thus permitting the closure element when inserted in said shell element, to project through the bottom portion thereof. The said shell element 36, is provided with internal grooves or channels 37, 38, and these grooves or channels communicate by means of vertical grooves 39, with each other and with the cup-like upper portion or mouth 40, of the shell element. Thus, when the closure element is fitted within the shell element, mercury poured into the upper portion 40, of the shell element, will gravitate through the grooves 39, into the respective grooves or channels 37, 38.

Also in Fig. 7 we have shown means for tying the closure element to the shell element to prevent accidental withdrawal of one from the other. While this tie or connecting feature may be of any suitable character, and is applicable in some manner to the other forms of our invention, it is represented in Fig. 7 as comprising an aperture 41, through the exposed lower end of closure element 35, said aperture being adapted to receive a spring member 42, which is caused to lie tensionally against the under surface of a flange 43, provided at the lower end of the shell element 36.

In Fig. 10 will be seen a form of our invention wherein the shell element 42^a, serves as the mercury sealing means at top and bottom of the closure element 43^a, said shell

element 42^a having a closed base, while the closure element is hollow, with a filling aperture 44, to receive mercury, and discharge orifices 45, 45, which respectively permit the outflow of mercury into the upper and lower portions of the shell element, to there form the respective seals at both sides of the communicable means through the stop-cock elements, without resorting to the use of annular grooves in either element.

Variations may be resorted to within the spirit and scope of our invention and parts thereof used without others.

We claim:—

1. In a stop-cock device, in combination, an open ended shell element, a hollow closure element to comprise a source of mercury supply, said elements interfitting and having transversely communicable means, including a tubular passage extended through said closure element, one of said elements having annular grooves at both sides of said communicable means, with orifices through which mercury from said supply source may enter said grooves to form a packing seal.

2. In a stop-cock device, in combination, an open ended shell element, a hollow closure element having an entrance and serving to comprise a source of mercury supply, a distensible, removable cover for said entrance, said elements interfitting and having transversely communicable means, and one of said elements having annular grooves at both sides of said communicable means, with orifices through which mercury from said supply source may enter said grooves to form a packing seal.

3. In a stop-cock device having a shell

element and a closure element to interfit in seating relation, said elements having transversely communicable means, in combination, a source of mercury supply for said device, an opening for said source, a distensible cover for said opening, and means for lodging mercury from said supply source as a packing seal at both sides of said communicable means.

4. In a stop-cock device having a shell element and a closure element to interfit in seating relation, said elements having transversely communicable means, in combination, a source of mercury supply for said device, an opening to said source, a stopper for said opening, said stopper having an air vent, and means for lodging mercury from said supply source as a packing seal at both sides of said communicable means.

5. In a stop-cock device, in combination, a shell element comprising a source of mercury supply, closed at its lower end and open at its upper end, a closure element to seat in said shell element, said elements having transversely communicable means, and one of said elements having annular grooves at both sides of said communicable means, also vertical grooves leading respectively from the upper and lower portions of one of said elements to said annular grooves, and exterior means of communication between the upper and lower portions of said shell element.

Signed at the borough of Manhattan, in the city, county, and State of New York, this 13th day of September, A. D. 1919.

AUGUST EIMER.

WILHELM T. WIEGAND.
